(57) **CLAIM**

The ornamental design for a clamp for extending height of cubicle walls, as shown and described.

DESCRIPTION

FIG. 1 is a top front perspective view of the clamp.

FIG. 2 is a bottom rear perspective view thereof.

FIG. 3 is a top front perspective view thereof, shown within the environment of use.

FIG. 4 is a front view thereof.

FIG. 5 is a rear view thereof.

FIG. 6 is a left-side view thereof.

FIG. 7 is a right-side view thereof.

FIG. 8 is a top view thereof; and,

FIG. 9 is a bottom view thereof.

The broken line showing of parts of FIG. 3 is included for the purpose of illustrating use and environment, and forms no part of the claimed design.

1 Claim, 6 Drawing Sheets
